(57) **CLAIM**

The ornamental design for a pet feeder as shown and described.

DESCRIPTION

FIG. 1 is a perspective view of a first embodiment of a pet feeder showing our new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a bottom perspective view of a second embodiment of the pet feeder, the front perspective view, the front elevational view, the rear elevational view, the left side elevational view, the right side elevational view, and the top plan view being same as those shown in FIG. 1 and FIGS. 3-7;

FIG. 10 is a bottom view thereof;

FIG. 11 is a perspective view of a third embodiment of a pet feeder showing our new design;

FIG. 12 is another perspective view thereof;

FIG. 13 is a front view thereof;

FIG. 14 is a rear view thereof;

FIG. 15 is a left side view thereof;

FIG. 16 is a right side view thereof;

FIG. 17 is a top view thereof;

FIG. 18 is a bottom view thereof;

FIG. 19 is a bottom perspective view of a fourth embodiment of the pet feeder, the front perspective view, the front elevational view, the rear elevational view, the left side elevational view, the right side elevational view, and the top plan view being same as those shown in FIG. 11 and FIGS. 13-17; and,

FIG. 20 is a bottom view thereof.

(Continued)

The dash-dash broken lines in the drawings depict portions of the pet feeder that form no part of the claimed design.
